UNITED STATES PATENT OFFICE.

DANIEL D. DANTZLER, OF CHESTER, SOUTH CAROLINA.

HORSE-DETACHER.

SPECIFICATION forming part of Letters Patent No. 296,142, dated April 1, 1884.

Application filed November 14, 1883. (No model.)

To all whom it may concern:

Be it known that I, DANIEL D. DANTZLER, a citizen of the United States of America, a resident of the town of Chester, in the county of Chester, in the State of South Carolina, have invented a new and useful Horse-Detaching Device, of which the following is a specification.

My invention relates to improved means for detaching horses from vehicles; and it consists 10 in a novel arrangement and combination of means fixed to a single-tree, whereby the traces of the harness may be unhitched simultaneously from the single-tree and the animal thus freed.

15 I effectuate the objects of my invention by means of the mechanism illustrated in the accompanying drawings, wherein Figure 1 is a plan view of a single-tree having my improvements attached. Fig. 2 is a longitudinal sectional view, showing the mechanism. Fig. 3 is 20 a view of the cord-pulleys fixed to the center of the single-tree; and Fig. 4 is a plan view, showing the improvements attached to a double-tree.

25 The letter A represents the metallic shell of the device, consisting, first, of the thimble B, made of suitable dimensions and fitted neatly over the prepared end of the single-tree; and, second, of the barrel C, which is an integral 30 part of the thimble B, the chambers being separated by the wall a, formed between them. The end of the barrel C is extended, and is provided with a trace-hole, b; also has the end perforated to receive the end of the trace-bolt when extended.

35 The letter D represents the bolt. This bolt is formed with the notches c and c', to receive the free end of a friction-spring, E, secured to the inner face of the thimble B, substantially 40 as shown. The bolt D is also slotted longitudinally, as shown at d, and a pin or bolt, e, is passed through the casing of the barrel and thimble, and through the slot in the bolt, which pin prevents the bolt from being entirely withdrawn from the barrel when the exigency arises to pull upon the cords. The rear or inner end of the bolt is provided with a perforation or other suitable means for receiving and attaching the cord. The movement of the bolt in 45 either direction is positive, and it is secured in its forward position, adapted to retain the trace, by the force of the spring in the notch

c, and retained in its withdrawn position by the same force acting in the notch c'.

The letter F represents a frame or casing 55 formed with clip-flanges g, fitted to the single-tree, and serving as the means by which it is secured thereto. The grooved pulleys G and G' are arranged within this casing, and the frame of the casing is provided with perforations h h' on each side, the one for the passage of the cord to the upper pulley and the other for the cord of the lower pulley, from whence they pass about the pulleys transversely, and thence up through a small hole in the front of 65 the vehicle directly opposite the center of the single-tree, and are arranged and secured to suit the convenience of the occupant of the vehicle. This arrangement of the cord-pulleys in a casing retains the cords so they cannot draw out 70 of the grooves of the pulleys. The casing is made, as stated, with flanges or clip-extensions, and may be of one piece, or in parts, as the maker may prefer. The cords are arranged close to the single-tree all the way from the 75 ends of the trace-bolts to the pulleys, so as to be free from objectionable contact with any part of the harness, vehicle, or animal.

Should it be desired to use this attachment when two horses are driven, it may be easily 80 accomplished by fastening an additional pulley-ease in the center of the buggy-body in front, and passing the cords from the center of the whiffletrees through this pulley and uniting them and then fastening the ends to the top of 85 the dash, or in any convenient place. The breast-strap may work in open hooks at the end of the pole, which will allow the horses to be liberated when the traces become detached.

In order to insure a free exit of the horse 90 when the traces are detached from the single-tree, the holdback-strap of the harness is adjusted to work against an iron cleat secured to the under side of the shaft, with its forward end free from contact with the shafts. The 95 holdback-strap is also connected, by means of a narrow strip of leather, with the saddle-tugs in which the shafts rest, and from thence the strip of leather extends to the buckle of the trace and is there secured. This arrangement, 100 it will be observed, affords means for pulling the shaft-tugs and the holdback-strap simultaneously from the shafts.

It will be observed that by my improved

means a horse can be instantly detached from a buggy, either while he is in motion or while standing. It will be further seen that there is no possible chance for the device to be accidentally operated, nor for the belts and cords to come in contact with the horse's tail.

The operation of the device is simple: To fasten the traces, insert the end of the trace in the opening and push the bolt forward 10 with the finger. To withdraw the bolts and release the animal, pull the cords, and the traces are released, and then the forward motion of the horse forces him from the shafts.

I am aware that detaching devices of the 15 character herein described have heretofore been made wherein the trace-bolts have been held in a forward position by means of a coil-spring, and in retracting position by a spring-latch, and also that cords have been led from 20 the trace-bolts about pulleys fixed to the central part of the single-tree. I do not claim either of these constructions. My improvement simplifies the old styles of detaching devices by dispensing with the spring for projecting the bolt and arranging a single friction-spring to hold the bolt in both its projected and its retracted positions.

What I claim as my invention, and desire to secure by Letters Patent, is—

1. In a horse-detaching device, the end clip, 30 A, consisting of the thimble B, having secured thereto the spring E, the barrel C, provided at its outer end with a trace-hole and perforation, substantially as described, and the notched bar D, in combination with the casing F, provided with holes h h', pulleys G G', inclosed within said casing, and the cords arranged to operate substantially as shown, and for the purpose set forth.

2. The casing F, provided with the clip flanges to embrace the single-tree, and having holes h h' for the cord, in combination with the inclosed pulleys G and G', mounted upon a common pin passing through the casing, substantially as described, and for the purpose set forth.

In testimony whereof I have hereunto affixed my signature in the presence of two attesting witnesses.

D. D. DANTZLER.
